WARP KNITTING MACHINE

Fritz Lambach, Tenafly, and Walter Siegel, Paramus, N. J.,
assignors to Robert Reiner Inc., Weehawken, N. J.

Application February 10, 1953, Serial No. 336,062

9 Claims. (Cl. 66—86)

This invention relates to warp knitting machines, and more particularly to the arrangement of hangers carrying the guide bars.

In the hitherto customary warp knitting machines, the hangers carrying the warp guides have the tendency to vibrate upwardly and downwardly in their bearings during the operation of the machine. Holding means, for example springs, necessary to counteract this undesired vibration, impede the manipulation of the hangers when they are manually lifted for threading operations or replacement of warp guides.

An object of this invention is to provide a hanger arrangement in a warp knitting machine, by means of which these undesired vibrations may be overcome without the use of holding means whereby the construction of the machine is simplified and the manipulation of the hangers is facilitated.

Another object of the invention is to improve on the construction of warp knitting machines as now ordinarily made.

Other objects and structural details of the invention will be apparent from the following description when read in conjunction with the accompanying drawings forming part of this specification, wherein:

Fig. 1 is a vertical sectional view of hanger arrangements for carrying guide bars of a warp knitting machine, and

Fig. 2 is a sectional view taken on line 2—2 of Fig. 1.

Referring now to the drawings, 10 generally indicates a guide bar shaft journaled in suitable bearings (not shown) of the frame of a warp knitting machine. Said guide bar shaft 10 is oscillated in a suitable manner known per se by a suitable mechanism of the warp knitting machine during the operation of the latter.

Groups of three brackets 12, 13 and 14 are arranged on the rockable guide bar shaft 10 in spaced relation to each other. Only one group is shown in the drawings. Each bracket 12, 13 and 14 is fixedly secured to the guide bar shaft 10 so that it participates in the rocking movements of the latter. The bracket 12 has a downward extension 16, the bracket 13 has a downward extension 17 and the bracket 14 has a downward extension 18.

Referring now to the bracket 13, a plate 20 is rigidly connected with bracket 13 and its downward extension 17 by means of screws 22. An upper pair of hooklike engaging elements 24 and a lower engaging element 26 is secured to said plate 20 by means of screws or the like. Said hooklike engaging elements 24 and 26 form a rectangular guiding slot 28 and 30 respectively in conjunction with an inclined surface of the plate 20. The axes *a* and *b* respectively of said rectangular guiding slots 28 and 30 respectively are arranged in a predetermined manner as will be described later on.

The upper bar 32 and the lower bar 34 of a hanger generally indicated by 36 (see Fig. 2) are slidably engaged with said upper and lower engaging elements 24 and 26 respectively.

2

The upper and lower bars 32 and 34 respectively are inserted into the guiding slots 28 and 30 respectively formed by the engaging elements in conjunction with the inclined surface of the plate 20. Thus, the hanger 36 is suspended from the bracket 13.

5 A guide bar 38 carrying a series of warp guides 40 is secured to the hanger 36 by screws 42.

During the operation of the warp knitting machine, the guide bar 38 extending longitudinally of the machine 10 may perform reciprocating movements in the direction of the double arrow A in response to a guide bar controlling mechanism known per se, the bars 32 and 34 of the hanger 36 sliding in the slots 28 and 30 in a direction parallel to the direction of the longitudinal axis of the machine.

Furthermore, as known per se, the guide bar 38 suspended through the medium of the hanger 36 from the bracket 13 is subject to rocking movements about the center B of the guide bar shaft 10 when the latter is 20 rocked during the operation of the machine.

Thus, during such rocking movements, a centrifugal force C is created which acts in the direction of a line *c* drawn between the center B of the shaft 10 and the center D of gravity of the suspended masses. The axes *a* and *b* of the rectangular guiding slots 28 and 30 are parallel to said line *c*. Therefore during the operation of the machine the bars 32 and 34 of the hanger 36 are urged against the lower surfaces 44 and 46 respectively of said guiding slots 28 and 30 respectively, whereby the hanger 36 is prevented from undesired vibrations upwardly and downwardly. The action of the centrifugal force C suffices to overcome the tendency of the hanger to vibrate upwardly and downwardly during the operation of the machine, so that hitherto customary means for holding 30 the bars 32 and 34 of the hanger 36 against the lower surface of the guiding slots may be omitted.

As best shown in Fig. 1, a plate 48 secured to the downward extension 16 of the bracket 12 is provided with hooklike engaging elements 50 and 52. Bars 54 and 56 40 of a hanger 58 carrying the rear guide bar 60 are slidably engaged with said engaging elements 50 and 52 respectively. The guiding slots 62 and 64 formed by said guiding elements 50 and 52 are tilted in such a way that their axes *d* and *e* are parallel to a line drawn between the center B of the guide bar shaft 10 and the center E of gravity of the suspended masses. Therefore the centrifugal force F acting in the direction of the line between the points B and E has the tendency to urge the bars 54 and 56 against the bottom of the guiding slots 50 62 and 64 so as to prevent the holder 58 and the guide bar 60 from an undesired vibration during the operation of the machine.

In a similar manner a plate 66 attached to the downward extension 18 of the bracket 14 is provided with 55 guiding elements 68 and 70 forming slots 72 and 74 respectively for engagement with bars 76 and 78 respectively of a hanger 80 carrying the front guide bar 82. Again the slots 72 and 74 are tilted so that their axes *f* and *g* are parallel to a line drawn between the center B of the guide bar shaft 10 and the center G of gravity of the suspended masses. Thus the centrifugal force H 60 acting along the line between the points B and G tends to hold the hanger 80 and the front guide bar 82 carried by the latter in their position during the operation of the machine.

In order to enable the operator of the machine to obtain ready access to the warp guides 84 of the rear warp guide 60, if for example yarns shall be threaded through the eyes of the warp guides 84, the warp knitting 70 machine is provided with mechanisms for lifting the intermediate guide bar 38 and front guide bar 52.

For this purpose a lifting finger 86 is arranged for cooperation with the bar 32 of the hanger 36 carrying the intermediate guide bar 38 and a lifting finger 88 is arranged for cooperation with the bar 76 of the hanger 80 carrying the guide bar 82.

As best shown in Fig. 1 the rear end of the lifting finger 86 secured to the shaft 90 is arranged in a recess 92 of the bracket 13. The front end portion of the lifting finger 86 passes through and projects from a slot 94 of the plate 20 attached to and rigid with the bracket 13. As best shown in Fig. 2, said slot 94 is between the pair of hook-like engaging elements 24. Thus, the lifting finger 86 is covered by the body of the bracket 13, so that yarns of the sheet of yarns extending from the warp beams to the warp guides 40 are prevented from entanglement with the lifting mechanism.

The shaft 90 rockably mounted in suitable bearings is rigidly connected with an arm 96, which in turn is pivotally connected with a rod 98 controlled in a suitable manner by an actuating mechanism (not shown) for actuating the lifting finger 86 at will.

In a similar manner, the lifting finger 88 secured to a rockable shaft 100 is covered by the bracket 14 and projects through and from a slot 102 of the plate 66. The lifting finger 88 may be actuated by the actuating mechanism (not shown) through the medium of the linkage 104, 106, 108.

We have described preferred embodiments of our invention, but it is understood that this disclosure is for the purpose of illustration, and that various omissions or changes in shape, proportion and arrangement of parts, as well as the substitution of equivalent elements for those herein shown and described may be made without departing in any way from the spirit and scope of this invention as set forth in the appended claims.

What we claim is:

1. In a warp knitting machine, the combination of: a rockable guide bar shaft, a bracket secured to said guide bar shaft, and a hanger suspended from said bracket and arranged for carrying a guide bar, said hanger being fully movable and liftable relative to said bracket in a direction substantially parallel and opposite to the direction of the centrifugal force generated upon a rocking movement of said guide bar shaft, said hanger being freely slideable with respect to said bracket.

2. In a warp knitting machine, the combination of: a rockable guide bar shaft, a bracket secured to said guide bar shaft, a hanger arranged for carrying a guide bar, first engaging means arranged on said bracket, and second engaging means arranged on said hanger and engaged with said first engaging means for suspending said hanger from said bracket, said cooperating engaging means being fully slideable relative to each other in a direction substantially parallel to the longitudinal axis of said guide bar shaft and in a direction substantially parallel to the direction of the centrifugal force generated upon a rocking movement of said guide bar shaft.

3. In a warp knitting machine, the combination of: a rockable guide bar shaft, a bracket secured to said guide bar shaft, and a hanger suspended from said bracket and arranged for carrying a guide bar, said hanger being freely movable and liftable relative to said bracket in a direction substantially parallel to a line connecting the center of said guide bar shaft with the center of gravity of the liftable masses in a plane perpendicular to the longitudinal axis of the guide bar shaft, said hanger being freely slideable with respect to said bracket.

4. In a warp knitting machine, the combination of: a rockable guide bar shaft, a bracket secured to said guide bar shaft, a hanger arranged for carrying a guide bar, first engaging means arranged on said bracket, and second engaging means arranged on said hanger and engaged with said first engaging means for suspending said hanger

from said bracket, said cooperating engaging means being freely slideable relative to each other in a direction substantially parallel to the longitudinal axis of said guide bar shaft and in a direction substantially parallel to a line connecting the center of said guide bar shaft with the center of gravity of the suspended masses in a plane perpendicular to the longitudinal axis of the guide bar.

5. In a warp knitting machine, the combination of: a rockable guide bar shaft, a group of a plurality of brackets secured to said guide bar shaft, said brackets being arranged behind one another, and a number of hangers equal to the number of brackets, each hanger being suspended from one of said brackets and being arranged for carrying a guide bar, each hanger being freely movable and liftable relative to its associated bracket in a direction substantially parallel and opposite to the direction of the centrifugal force generated upon a rocking movement of said guide bar shaft.

6. In a warp knitting machine, the combination of: a rockable guide bar shaft, a group of a plurality of brackets secured to said guide bar shaft, said brackets being arranged behind one another, a number of hangers equal to the number of brackets, each hanger being associated with one of said brackets and being arranged for carrying a guide bar, first engaging means arranged on each bracket, and second engaging means arranged on each hanger, said second engaging means of each of said hangers being engaged with said first engaging means of an associated bracket for suspending said hanger from its associated bracket, said cooperating engaging means of each associated bracket and hanger being freely slideable relative to each other in a direction substantially parallel to the longitudinal axis of said guide bar shaft and in a direction substantially parallel to the direction of the centrifugal force generated upon a rocking movement of said guide bar shaft.

7. In a warp knitting machine, the combination of: a rockable guide bar shaft, a bracket secured to said guide bar shaft, a hanger suspended from said bracket and arranged for carrying a guide bar, said hanger being liftable relative to said bracket in a direction substantially parallel and opposite to the direction of the centrifugal force generated upon a rocking movement of said guide bar shaft, said bracket having a slot, and a rockable lifting element, said lifting element passing through said slot and being arranged for cooperation with said hanger.

8. In a warp knitting machine, the combination of: a rockable guide bar shaft, a bracket secured to said guide bar shaft, a hanger liftable suspended from said bracket and arranged for carrying a guide bar, said bracket having a slot, and a rockable lifting element, said lifting element passing through said slot and being arranged for cooperation with said hanger.

9. In a warp knitting machine, the combination of: a rockable guide bar shaft, a bracket secured to said guide bar shaft, a pair of spaced engaging elements arranged on said bracket, a hanger for carrying a guide bar, said hanger being slidably engaged with said pair of engaging elements, said bracket having a slot between said spaced engaging elements, and a rockable lifting element, said lifting element passing through said slot and being arranged for cooperation with said hanger.
